CLAIM

The ornamental design for a keg cap holder, as shown and described.

DESCRIPTION

FIG. 1 is a perspective view of a keg cap holder showing our new design.

FIG. 2 is a back perspective view of the keg cap holder.

FIG. 3 is a front view of the keg cap holder.

FIG. 4 is a rear view of the keg cap holder.

FIG. 5 is a top view of the keg cap holder.

FIG. 6 is a bottom of the keg cap holder.

FIG. 7 is a left side view of the keg cap holder; and,

FIG. 8 is a right side view of the keg cap holder.

The broken lines shown in the Figures illustrate portions of the key cap holder forming no part of the claimed design.
